U.S. Cl. 23—230

5 Claims

ABSTRACT OF THE DISCLOSURE

Process for the colorimetric determination of 17-keto-steroids in urine or blood comprising hydrolysing urine or blood in a strongly acid media for 12 to 14 minutes with boiling, cooling to the ambient temperature and extracting with a slightly water-soluble solvent, washing this extract with an aqueous alkaline liquid, eliminating the solvent by evaporation, cooling, taking up the dry residue with a solution of m-dinitrobenzene in a solvent, adding a solution of potassium hydroxide, allowing the mixture to rest, diluting with a polar solvent, comparing the extinction of the resulting colored solution with a sample of defined concentration in order to know the initial concentration of 17-ketosteroids in the blood or the urine, the potassium hydroxide solution consisting of a stabilized solution in an anhydrous alcohol at a concentration of 3 to 6 N, the contact time between the m-dinitrobenzene solution containing the residue and the potassium hydroxide solution before the dilution with the said polar solvent being about 25 minutes, this polar diluting solvent being an anhydrous polar solvent.

It is already known to determine steroids having 19 carbon atoms and bearing a keto group in the 17 position, which are generally known under the name of neutral 17-ketosteroids, by making them react in a strong alkaline medium with m-dinitrobenzene, which produces a violet color which remains stable for several hours. In the presence of an excess of m-dinitrobenzene, the optical density (O.D.) is proportional to the amount of 17-ketosteroids. Reference is hereby made to the following known conventional methods:

15 However, these methods suffer from the following disadvantages:

(1) Colorimetric aqueous solutions are relatively unstable having a stability of at the most 7 minutes.

20 (2) The alcoholic solutions usually used are not stable or the blank tests are not readable or must be made up each time on the day of use.

(3) Consequently, the work is laborious.

25 (4) They make impossible the practical realization of hormonal analysis at the same time as other chemical clinical tests.

(5) Most normal contents of steroids accumulated in man and determined by other technics are very generalized and render their clinical interpretation incoherent and difficult and sometimes impossible.

30 (6) Some of these process have recourse to toxic reagents, for example, carbon tetrachloride and ethylene dichloride.

35 The present invention has for its object to obviate these disadvantages.

Owing to the use of stable solutions, it permits to make analysis in a reduced time of only about 70 minutes. It makes possible to carry out other clinical chemical laboratory analysis at the same time as the hormone analysis while avoiding the use of all toxic reagents and solvents.

40 The invention has for its object a process for the colorimetric determination of 17-ketosteroids in urine or blood comprising hydrolysing urine or blood in a strongly acid media for 12 to 14 minutes with boiling, cooling to the ambient temperature and extracting with a slightly water-soluble solvent, washing this extract with an aqueous alkaline liquid, eliminating the solvent by evaporation, cooling, taking up the dry residue with a solution of

50 m-dinitrobenzene in a solvent, adding a solution of potassium hydroxide, allowing the mixture to rest, diluting with a polar solvent, comparing the extinction of the resulting colored solution with a sample of defined concentration in order to know the initial concentration of 17-ketosteroids

55 in the blood or the urine, the potassium hydroxide solution consisting of a stabilized solution in an anhydrous alcohol at a concentration of 3 to 6 N, the contact time between the m-dinitrobenzene solution containing the residue and the potassium hydroxide solution before the dilution with the said polar solvent being about 25 minutes, this polar diluting solvent being an anhydrous polar solvent.

EXAMPLE

60 65 Determination of 17-ketosteroids are made on 24 hour-old urines from which an aliquot part is taken, generally from 2 to 10 ml. In a test tube equipped with a ground stopper, is placed 10 ml. of the urine to be analyzed and 2 ml. of concentrated hydrochloric acid or 2 ml. of 11 M sulfuric acid. This mixture is hydrolysed in a boiling steam bath for 13 minutes. It is cooled and then extracted by 20 ml. of ether. It is shaken about 50 times. The layers are

allowed to separate for 2 to 3 minutes and the aqueous layer is removed. The ethereal layer is then washed successively with portions of 2 ml. of 4 N sodium hydroxide and 2 ml. of distilled water, rejecting the aqueous layers. There are taken then 3 aliquots, each of 4 ml. of the ethereal extract which are left in three test tubes marked UB, U₁ and U₂. These three ethereal aliquots are evaporated to dryness by plunging them in a steam bath at temperature not much in excess of 40° C. The test tubes are wiped, cooled and colored at the same time as the aliquots of the samples of 10 to 40 microgrammes already evaporated to dryness at the moment of the hydrolysis of urine in the boiling water (B.M.). These test tubes are colored by adding in a test tube of urinary extract, 0.4 ml. of absolute alcohol as a blank test for extract (UB) and 0.4 ml. of an alcoholic solution of m-dinitrobenzene (1) in an empty and dry test tube used as a blank test for the reagents (RB) and the two test tubes of urinary extract as well as in all the test tubes of the aliquots of the standard, by adding in all the test tubes 0.3 ml. of the 3 to 6 N solution of potassium hydroxide in an anhydrous alcohol stabilized with a mixture of p-dimethylphenyl-

enediamine-sulfate, ascorbic acid, benzoic acid and anhydrous sodium sulfate. The whole is well mixed in order to dissolve the dry extract in the test tubes. They are left in the absence of light for 25 minutes. There is added 5 ml. of anhydrous polar solvent, for example absolute alcohol. The whole is mixed. The optical density of these various mixtures is then read at 515 m μ (50 to 525 m μ) on a spectrophotometer or a photometer. Test tube (UB) is read against absolute alcohol and U₁, U₂ and the standards against (RB). The concentration of the 17-ketosteroids in the urine, by comparing an average of the optical density of two urinary extracts (U₁ and U₂) less the absorption of (UB), is evaluated against a chart indicating the average optical density as read on the spectrophotometer or photometer for various concentrations of the standard used as reference in the test. The optical density of a standard containing for instance 10 micro-grams of DHEA (by dehydroepiandrosterone is 0.095±0.01 as read on a Beckmann (DU model) spectrophotometer.

Obtained by the process of the invention, the normal contents in 17-ketosteroids in men and women established according to the age vary as shown in the two tables below.

In accord with this convention the preferred range of constituents for the stabilized alcoholic 3 N to 6 N KOH is the following:

	G./l.
p-dimethylphenylenediamine sulfate	.01 to 10
Ascorbic acid	.01 to 100
Benzoic acid	0.01 to 200
Sodium sulfate	1 to 200

The alcohols used for this solution are preferably lower alkyl alcohols having 1 to 8 carbon atoms.

Among the advantages of the invention is the fact that the solution can be successively used in auto-dialyzing apparatus with colorimetric adaptations.

The process and solutions of this invention are also adapted to the determination of other steroids after transforming them into 17-ketosteroids. Such other steroids include α, β -17-ketosteroids, total estrogens and estrogen fractions. The invention also is of value in determining the diagnostic relation of 17-ketosteroids and 17-hydroxy-steroids of import in cancer detection.

What is claimed is:

1. A process for the colorimetric determination of 17-ketosteroids in urine or blood comprising hydrolyzing urine or blood by boiling in a strongly acid medium for 12 to 14 minutes, cooling the thus hydrolyzed solution to ambient temperature and extracting said solution with a slightly water-soluble solvent; washing this extract successively with a 4 N aqueous solution of sodium hydroxide and distilled water to eliminate undesirable chromogens and concentrating the purified extract to dryness by evaporating said solvent; cooling the dry residue and dissolving it in an alcoholic solution of m-dinitrobenzene and adding to the thus-colored solution a 3 to 6 N potassium hydroxide solution in an anhydrous alkanol having one to eight carbon atoms per molecule and stabilized with para-dimethyl-phenylenediamine sulfate, ascorbic acid, benzoic acid and sodium sulfate, allowing the mixture to rest and then diluting it with a polar solvent; and comparing with a spectrophotometer or with a photometer the extinction of the colored solution with the extinction of a

similarly treated solution of 17-ketosteroids of known concentration, at 510 to 525 μ .

2. A process as claimed in claim 1, in which the anhydrous alcohol used for preparing the 3 to 6 N potassium hydroxide solution is anhydrous methanol.

3. A process as claimed in claim 1, in which said strongly acidic medium is a member selected from the class consisting of concentrated hydrochloric acid and 11 M sulfuric acid.

4. A process as claimed in claim 1, in which said stabilizing agents are present in the potassium hydroxide solution in the following concentration:

	G./l.
Para-dimethylphenylenediamine sulfate	0.1 to 10
Ascorbic acid	0.01 to 100
Benzoic acid	0.01 to 200
Sodium sulfate	1 to 200

5. A reagent for performing the process for the colorimetric determination of 17-ketosteroids as claimed in claim 1, consisting essentially of a 3 to 6 N potassium hydroxide solution in anhydrous alkanol having one to eight carbon atoms per molecule and containing 0.01 to 10 g./l. of para-dimethylphenylenediamine sulfate, 0.01 to 100 g./l. of ascorbic acid, 0.01 to 200 g./l. of benzoic acid and 1 to 200 g./l. of sodium sulfate.
